RAILWAY SIGNAL CONTROL APPARATUS
FOR PROTECTING AGAINST MOMENTARY
LOSS OF TRACK SHUNTOtto W. Rost, Chicago, Ill., assignor to Westing-
house Air Brake Company, a corporation of
Pennsylvania

Application May 26, 1949, Serial No. 95,498

12 Claims. (Cl. 246—41)

1

My invention relates to railway signal control apparatus for protecting against a momentary loss of shunt of a track circuit for a given track section while the given track section is occupied by a train. More specifically, my invention relates to an arrangement for controlling a railway signal which governs traffic movements onto the given section so that it will not display a false proceed indication momentarily, but will display the stop indication without interruption, in the event of a momentary reduction or loss of track shunt of the track circuit for the given track section while the given track section is occupied by a car or train.

It sometimes happens that a track relay becomes sufficiently energized to close its front contacts for a brief period of time while a car or train is moving over the associated track section. This is more possible when a single car or a short train moves over the track section, and particularly if the car or train is of light weight. Such false energization of a track relay may be due to some material such, for example, as dirt, grease, or sand between the rails of the track and the wheels of the train. The presence of such material between the rails of the track and the wheels of the train may introduce momentarily so much resistance into the multiple shunting paths across the rails, through the wheels and axles of a train, that track battery current of sufficient magnitude can pass through the control winding of the track relay to effect closure of the front contacts of the track relay.

It follows that, if a signal operating circuit controlled by a front contact of a track relay becomes closed as soon as the front contact of the track relay is closed, the signal may be operated to display a false proceed indication for a brief period of time while it should be displaying the stop indication. Obviously, such operation of a signal might result in unsafe operation of a train, and should therefore be prevented.

An object of my invention is therefore the provision of novel and improved means to insure that a false proceed indication is not momentarily displayed, but that the stop indication is uninterruptedly displayed, by a railway signal when a track relay by which the signal is controlled becomes energized and closes its front contacts during a momentary reduction, or loss, of shunt of the track circuit with which the track relay is associated.

A feature of my invention, for attaining this object, is the provision of an arrangement for delaying operation of a railway signal by retaining

2

the operating circuit for the signal in its deenergized condition during a brief period after the front contacts of a track relay by which the signal is controlled become closed.

- 5 In my invention, means for retaining the operating circuit for a signal in its deenergized condition during such brief periods includes a directional stick relay which becomes energized when a train passes the signal onto a given track section 10 while the signal is displaying a proceed indication for directing traffic movements in a given direction onto the given track section. A stick circuit for retaining the directional stick relay energized after the signal changes from the proceed to the stop indication is controlled by a contact operated by a time element device, so that it is closed while the time element device is deenergized, and becomes opened after the time element device has been energized for a measured 15 period of time.

An operating element for the signal is controlled by a back contact of the directional stick relay, and an auxiliary relay is connected with the signal control circuit through a front contact 20 of the directional stick relay.

An energizing circuit for the time element device is controlled by a front contact of the stick relay and by a front contact of the auxiliary relay.

- 30 A control circuit for an opposing signal which directs traffic movements in the opposite direction onto the given track section is controlled in part by the contact of the time element device and by a back contact of the stick relay.

35 I shall describe one form of apparatus embodying my invention, and shall then point out the novel features thereof in claims.

- The accompanying drawing is a diagrammatic view showing one form of apparatus embodying 40 my invention, in which a signal for governing traffic movements onto a given track section in a given direction is controlled, to display a proceed indication, by a circuit including a front contact of a track relay for the given track section 45 and the back point of a contact of a directional stick relay; in which the directional stick relay becomes energized in response to a train entering the given track section in the given direction while the signal is controlled to display a proceed indication; in which an auxiliary relay is controlled over a portion of the signal control circuit, including the track relay contact, through the front point of a contact of the directional stick relay; in which a time element device is 50 controlled by a circuit including front contacts 55

of the stick and auxiliary relays; and in which a contact of the time element device opens a stick circuit for the directional stick relay upon the lapse of a measured period of time after the track relay closes its front contact, so that the contact of the stick relay is again closed at its back point in the control circuit for the signal.

Similar reference characters refer to similar parts in the drawing.

Referring further to the drawing, a stretch of 10 single track railway is shown connected by a track switch W with a siding Z . The single track stretch is divided by insulated joints 5 into sections designated by the reference characters $1T$, $3T$, and $4T$. Each of these track sections is provided with a track circuit including a suitable source of current such as a battery 6 , connected across the rails adjacent one end of the section, and a track relay, designated by the reference character TR preceded by a numeral which is the same as the numeral in the reference character for the associated track section, connected across the rails adjacent the opposite end of the section.

In order to simplify the drawing, each track, comprising two parallel series of track rails, is represented by a single line.

A pair of signals, designated by the reference characters $1S$ and $2S$, for governing traffic movements in opposite directions, is located adjacent insulated joints 5 between sections $1T$ and $3T$. A second pair of signals, designated by the reference characters $3S$ and $4S$, for governing traffic movements in opposite directions, is located adjacent the insulated joints 5 between sections $3T$ and $4T$. Signals $1S$ and $2S$ may be referred to as head block signals, and signals $3S$ and $4S$ may be referred to as intermediate signals. Signal $1S$ may also be referred to as an entering signal, and signal $2S$ may be referred to as a leaving or starting signal.

I shall assume that traffic movements toward the left, as shown in the drawing, are in the westbound direction, whereas traffic movements toward the right, as shown in the drawing, are in the eastbound direction. Signals $1S$ and $3S$ accordingly govern westbound traffic movements, and signals $2S$ and $4S$ govern eastbound traffic movements.

The signals may be of any suitable design such, for example, as the well-known search-light type. A signal of this type comprises various parts, which I have grouped together for signal $3S$, for example, and designated as a signal mechanism m , preceded by a numeral which is the same as the numeral in the reference character for the associated signal. Each of the signal mechanisms such, for example, as signal mechanism $3m$ shown for signal $3S$, comprises an optical unit which has a single lamp E and an operating element comprising a member 7 mounted to rotate in both directions as controlled by a signal winding 8 . Attached to member 7 , for rotation therewith between a normal position to the right and a reverse position to the left, are three colored filters or roundels, designated by the reference characters G , R , and Y , which may be of the colors green, red, and yellow, respectively. Member 7 is biased to a mid stroke or intermediate position to which it therefore moves when the associated signal winding 8 is deenergized. When signal winding 8 is energized by current of the polarity which I shall term normal polarity, member 7 is moved to the right-hand position, and when

winding 8 is energized by current of the opposite or reverse polarity, member 7 is moved to the left-hand position.

For convenience in illustration, lamp E is shown above the roundels, but it is to be understood that lamp E is actually located directly behind one of the roundels according to the position of the member 7 . Roundel G , R , or Y is moved in front of lamp E according as member 7 is moved to its right-hand position, its intermediate position, or its left-hand position, respectively.

The signal displays a clear proceed indication, an approach proceed indication, or the stop indication when roundel G , Y , or R , respectively, is placed in front of lamp E .

Operatively connected with member 7 is a circuit controller comprising two movable contact fingers 9 and 10 . Contact finger 9 engages a fixed contact element $9a$ when member 7 occupies its right-hand position, and engages a fixed contact element $9b$ when member 7 occupies either its intermediate or its left-hand position. Contact finger 10 engages a fixed contact element $10a$ when member 7 occupies its left-hand position, and engages a fixed contact element $10b$ when member 7 occupies either its intermediate or its right-hand position.

A signal of the type described is disclosed and claimed in Letters Patent of the United States No. 1,864,224, granted June 21, 1932, to Wesley B. Wells, for Light Signals.

Proceed signal repeater relays designated by the reference characters $2GYPR$ and $4GYPR$ are controlled by the circuit controllers for signals $2S$ and $4S$, respectively, so that each of these relays is energized when the member 7 of the associated signal is in either its left-hand or its right-hand position, but is deenergized when the member 7 of the associated signal is in its intermediate position. Each of the relays $2GYPR$ and $4GYPR$ is made slow releasing by an asymmetric unit 11 connected in multiple with the winding of the relay. Asymmetric units 11 may be of any suitable design such, for example, as the well-known copper oxide half-wave rectifier.

A clear signal repeater relay, designated by the reference character $1GPR$, is controlled by the circuit controller for signal $1S$ so that this relay is energized when the member 7 of signal $1S$ is in its right-hand position, but is deenergized when the member 7 of signal $1S$ is in the left-hand or the intermediate position. Relay $1GPR$ is made slow releasing, similarly to relays $2GYPR$ and $4GYPR$, by an asymmetric unit 11 connected across its control winding.

Associated with signals $2S$ and $4S$ are directional stick relays designated by the reference characters $2SR$ and $4SR$, respectively. Relays $2SR$ and $4SR$ become energized by pickup circuits controlled in part by contacts 23 and 27 of relays $2GYPR$ and $4GYPR$, respectively, and in part by back contacts 22 and 26 of track relays $3TR$ and $4TR$, respectively. It follows that each of the directional stick relays, as will be described in detail, becomes energized when a train, moving in the direction for which the associated signal governs traffic movements, passes the associated signal while the associated signal is controlled to display either of its two proceed indications. Each of the stick relays $2SR$ and $4SR$ then remains energized by a stick circuit controlled by a contact 16 or 28 of a time element device $2TE$ or $4TE$, respectively.

Each of the time element devices $2TE$ and $4TE$

is normally deenergized, and opens its contact upon the lapse of a measured period of time after its control element becomes energized.

Signal winding 8 of signal 2S is controlled by normal and reverse control circuits which include a front contact 13 of track relay 3TR for the track section 3T onto which signal 2S governs traffic movements. The control circuit for winding 8 of signal 2S also includes the back point of a contact 14 of relay 2SR. An auxiliary relay 2SRP, associated with signal 2S, is controlled through the front point of contact 14 of relay 2SR over a portion of the control circuit for winding 8 of signal 2S.

Time element device 2TE is controlled by front contacts 24 and 25 of relays 2SRP and 2SR, respectively, and time element device 4TE is controlled by front contacts 30 and 31 of relays 4SR and 4GYPR, respectively.

Signal control winding 8 of mechanism 3m of signal 3S is controlled by normal and reverse control circuits which include contact 16 of time element device 2TE and the back point of a contact 17 of relay 2SR. Signal winding 8 of signal 4S may be controlled by normal and reverse control circuits which are similar to those shown for signal 3S.

Signal control winding 8 of signal 1S may be controlled by normal and reverse control circuits which are similar to the circuits shown for signal 3S in a patent application of common ownership Serial No. 53,112, filed October 6, 1948 by James H. Butridge and William H. Claus, now Patent No. 2,546,331, for Railway Signal Control Systems.

Having described, in general, the arrangement and control of the various parts of apparatus embodying my invention, I shall now describe the circuits and operation in detail.

As shown in the drawing, all parts of the apparatus are in the normal condition, that is, track sections 1T, 3T, and 4T are unoccupied, and therefore track relays 1TR, 3TR, and 4TR are energized; each of the signal windings 8 is energized by current of normal polarity, and therefore each of the signals is controlled to display the clear proceed indication; each of the proceed signal repeater relays 2GYPR and 4GYPR and the clear signal repeater relay 1GPR is energized; and relays 2SR, 4SR, and 2SRP, and time element devices 2TE and 4TE are deenergized.

The circuit by which winding 8 of signal 2S is energized by current of normal polarity passes from terminal B of a suitable source of current, shown as a battery Q, through the back point of contact 12 of relay 4SR, contact 13 of relay 3TR, back point of contact 14 of relay 2SR, winding 8 of signal 2S, and the back point of contact 15 of relay 4SR to terminal N of the same source of current, battery Q. The circuit by which winding 8 of signal 3S is energized by current of normal polarity passes from terminal B, through contact 16 of device 2TE, back point of contact 17 of relay 2SR, contact 18 of relay 1TR, front point of contact 19 of relay 1GPR, winding 8 of signal 3S, contact 20 of relay 3TR, and the front point of contact 21 of relay 1GPR to terminal N.

Relay 2GYPR is energized by current passing from terminal B, through contacts 10-10b and 9-9a of signal 2S, and the winding of relay 2GYPR in multiple with asymmetric unit 11 in the high resistance direction, to terminal N. Relay 4GYPR is energized by a similar circuit controlled by contacts 10-10b and 9-9a of signal 4S. Relay 1GPR is energized by a circuit

passing from terminal B, through contacts 10-10b and 9-9a of signal 1S, and the winding of relay 1GPR in multiple with the asymmetric unit 11 in the high resistance direction, to terminal N.

I shall assume that, with apparatus embodying my invention arranged as shown in the accompanying drawing, an eastbound train approaches signals 1S and 2S, causing signal 1S to display the stop indication. Contacts 10-10b and 9-9a of signal 1S will therefore be opened, causing relay 1GPR to be deenergized. With relay 1GPR deenergized, its contacts 19 and 21 will now be closed at their back points, so that winding 8 of signal 3S will now be energized by current of reverse polarity in a circuit which is the same as the circuit previously traced for this winding except that it includes the back points of contacts 19 and 21 of relay 1GPR instead of the front points of these contacts. Member 7 of signal 3S will therefore move to its left-hand position, in which roundel Y is in front of lamp E, so that now signal 3S will display the approach proceed indication.

When the train enters section 1T, winding 8 of signal 3S will be deenergized because contact 18 of relay 1TR will be opened. Member 7 of signal 3S will therefore move to its intermediate position, in which roundel R is in front of lamp E so that now signal 3S will display the stop indication.

When the train enters section 3T, contact 13 of relay 3TR will open the circuit previously traced for winding 8 of signal 2S, causing this winding to be deenergized. Signal 2S will therefore now display the stop indication, and contact 9-9a of signal 2S will be open while contact 10-10a will still be open, and therefore relay 2GYPR will be deenergized.

With relay 3TR deenergized, the circuit for winding 8 of signal 3S will now be open at a second point on account of contact 20 of relay 3TR being open.

Relay 2GYPR, on account of being slow releasing, retains its contact 23 closed for a brief period of time, so that relay 2SR becomes energized by a pickup circuit passing from terminal B, through contact 22 of relay 3TR, contact 23 of relay 2GYPR, and the winding of relay 2SR to terminal N. Relay 2SR, upon becoming energized, completes its own stick circuit passing from terminal B, through contact 16 of time element device 2TE, front point of contact 17 of relay 2SR, and the winding of relay 2SR to terminal N.

With contact 17 of relay 2SR now open at its back point, the circuit for winding 8 of signal 3S is open at a third point.

When the train leaves section 1T, signal 1S will again be operated to the clear proceed position. Relay 1GPR will therefore again be energized by its circuit previously traced.

I shall now assume further that, while the train is on section 3T, there is a momentary loss of shunt of the track circuit for section 3T, so that relay 3TR closes its front contacts for a brief period of time. Relay 2SRP will therefore now be energized by a circuit passing from terminal B, through the back point of contact 12 of relay 4SR, contact 13 of relay 3TR, front point of contact 14 of relay 2SR, winding of relay 2SRP, and the back point of contact 15 of relay 4SR to terminal N.

Time element device 2TE will then also be energized by its circuit passing from terminal B, through contacts 24 and 25 of relays 2SRP and

2SR, respectively, and the control element of device 2TE to terminal N. Device 2TE is so designed and constructed that the time required for its contact 16 to open is longer than the period of a momentary loss of shunt of a track circuit.

Therefore, relay 3TR will again be deenergized and its contact 13 will open before the stick circuit for relay 2SR is opened by contact 16 of relay 2TE. Relay 2SR will therefore remain energized, and winding 8 of signal 2S therefore remains deenergized, and so signal 2S will not momentarily display a proceed indication, but will display the stop indication uninterruptedly during the occurrence of the momentary loss of shunt.

When the train enters section 4T, signal 4S will be controlled to display the stop indication. With signal 4S indicating stop, relay 4GYPR will now be deenergized. However, since relay 4GYPR is slow releasing, relay 4SR will become energized by its pickup circuit passing from terminal B, through contact 26 of relay 4TR, contact 27 of relay 4GYPR, and the winding of relay 4SR to terminal N. A stick circuit for relay 4SR will then be completed, passing from terminal B, through contact 28 of device 4TE, contact 29 of relay 4SR, and the winding of relay 4SR to terminal N.

When the train leaves section 3T, relay 2SRP again becomes energized by a circuit which is the same as the circuit previously traced except that it includes the front points of contacts 12 and 15 of relay 4SR instead of the back points of these contacts. Time element device 2TE will then again become energized by its circuit previously traced.

Upon the lapse of a measured period of time, contact 16 of device 2TE will open the stick circuit previously traced for relay 2SR, causing relay 2SR to become deenergized. When relay 2SR becomes deenergized, its contact 14 becomes opened at the front point, thereby deenergizing relay 2SRP, and contact 25 opens the circuit traced for device 2TE, so that device 2TE becomes deenergized.

When contact 14 of relay 2SR becomes closed at its back point, winding 8 of signal 2S will be energized by current of reverse polarity in a circuit which is the same as the circuit previously traced for this relay except that it includes the front points of contacts 12 and 15 of relay 4SR instead of the back points of these contacts. Signal 2S will therefore now be operated to its position in which roundel Y is in front of lamp E. Signal 2S will therefore now display the approach proceed indication. Relay 2GYPR will therefore now be energized by a circuit passing from terminal B, through contact 10-10a of signal 2S, and the winding of relay 2GYPR in multiple with asymmetric unit 11 in the high resistance direction, to terminal N.

With relay 2SR and time element device 2TE deenergized, the normal control circuit previously traced for signal 3S will again become closed when contact 16 of device 2TE closes.

When the train has proceeded far enough so that signal 4S is again displaying a proceed indication, relay 4GYPR will again become energized, and time element device 4TE will then be energized by a circuit passing from terminal B, through contact 30 of relay 4SR, contact 31 of relay 4GYPR, and the control element of device 4TE to terminal N. Upon the lapse of a measured period of time, contact 28 of device 4TE will

open the stick circuit for relay 4SR, causing relay 4SR to become deenergized.

Winding 8 of signal 2S will then again become energized by current of normal polarity in its circuit first traced, so that signal 2S will then again display the clear proceed indication.

Although I have herein shown and described only one form of apparatus embodying my invention, it is understood that various changes and modifications may be made therein within the scope of the appended claims without departing from the spirit and scope of my invention.

Having thus described my invention, what I claim is:

15. 1. In combination, a section of railway track, a railway signal for governing traffic movements in a given direction onto said section, a track circuit for said section including a track relay, a directional stick relay, an auxiliary relay, a control circuit for controlling said signal to display a proceed indication including a front contact of said track relay and the back point of a contact of said stick relay, a control circuit for said auxiliary relay including said front contact of said track relay and the front point of said contact of said stick relay, a pickup circuit for energizing said stick relay when a train enters said section while said signal is controlled to display a proceed indication, a time element device, a contact operated by said time element device normally closed while said time element device is deenergized but becoming opened after said time element device has been energized a measured period of time, a stick circuit for said stick relay controlled by said contact of said time element device, an energizing circuit for said time element device controlled by a front contact of said stick relay and by a front contact of said auxiliary relay, a second railway signal for governing traffic movements in the opposite direction onto said section, and a control circuit for controlling said second signal to display a proceed indication controlled in part by said contact of said time element device and by a back contact of said stick relay.
20. 2. In combination, a section of railway track, a railway signal for governing traffic movements in a given direction onto said section, a track circuit for said section including a track relay, a directional stick relay, an auxiliary relay, a control circuit for controlling said signal to display a proceed indication including a front contact of said track relay and the back point of a contact of said stick relay, a control circuit for said auxiliary relay including said front contact of said track relay and the front point of said contact of said stick relay, a pickup circuit for energizing said stick relay when a train enters said section while said signal is controlled to display a proceed indication, a time element device, a contact operated by said time element device normally closed while said time element device is deenergized but becoming opened after said time element device has been energized a measured period of time, a stick circuit for said stick relay controlled by said contact of said time element device, and an energizing circuit for said time element device controlled by a front contact of said stick relay and by a front contact of said auxiliary relay.
25. 3. In combination, a section of railway track, a railway signal for governing traffic movements in a given direction onto said section, a track circuit for said section including a track relay, a directional stick relay, an auxiliary relay, a circuit for

operating said signal to display a proceed indication controlled by a front contact of said track relay, and by a back contact of said stick relay, a circuit controlled by a front contact of said track relay and by a front contact of said stick relay for energizing said auxiliary relay, a pickup circuit for energizing said stick relay if a train enters said section while said signal is controlled to display a proceed indication, a normally closed contact, a stick circuit for said stick relay controlled by said normally closed contact, and means controlled by a front contact of said stick relay and by a front contact of said auxiliary relay for opening said normally closed contact.

4. In combination, a section of railway track, a railway signal for governing traffic movements in a given direction onto said section, a track circuit for said section including a track relay, a directional stick relay, means controlled by a front contact of said track relay and by a back contact of said stick relay for controlling said signal for displaying a proceed indication, a pickup circuit for energizing said stick relay when a train enters said section while said signal is controlled for displaying a proceed indication, a normally closed contact, a stick circuit for said stick relay controlled by said normally closed contact, and means controlled by front contacts of said track and stick relays for opening said normally closed contact.

5. In combination, a section of railway track, a railway signal for governing traffic movements onto said section, a track circuit for said section including a track relay, a control circuit including a front contact of said track relay for controlling said signal for displaying a proceed indication, and an arrangement embodying time element means controlled by means including a front contact of said track relay for delaying operation of said signal for displaying a proceed indication by retaining said control circuit in the deenergized condition for a brief period of time after said front contact of said track relay closes when said track relay becomes energized after having been deenergized.

6. In combination, a section of railway track, a railway signal for governing traffic movements onto said section, a track circuit for said section including a track relay, control means including a front contact of said track relay for controlling said signal for displaying a proceed indication, and an arrangement for delaying operation of said signal for displaying a proceed indication including a directional stick relay which becomes energized and deenergizes said control means in response to a train entering said section while said signal is controlled to display a proceed indication and said directional stick relay is then retained in the energized condition by a stick circuit, and time element means controlled by a front contact of said track relay and by a front contact of said stick relay for opening said stick circuit upon the lapse of a measured period of time after said track relay becomes energized.

7. In combination, a section of railway track, a railway signal for governing traffic movements onto said section, a track circuit for said section including a track relay, a control circuit including a front contact of said track relay for controlling said signal for displaying a proceed indication, a directional stick relay, a pickup circuit for energizing said stick relay when a train enters said section while said signal is controlled to display a proceed indication, a stick circuit for then retaining said stick relay in the energized condition, 75

means controlled by said stick relay for opening said signal control circuit when said stick relay becomes energized, and time element means for opening said stick circuit upon the lapse of a measured period of time after said track relay becomes energized.

8. In combination, a section of railway track, a railway signal for governing traffic movements onto said section, a track circuit for said section including a track relay, a control circuit including a front contact of said track relay for controlling said signal to display a proceed indication, a directional stick relay, a pickup circuit controlled by a train for energizing said stick relay when said train enters said section while said signal is displaying a proceed indication, a stick circuit including a front contact of said stick relay for then retaining said stick relay in the energized condition, means controlled by said stick relay upon becoming energized for opening said signal control circuit, and time element means controlled by said track relay and by said stick relay for opening said stick circuit upon the lapse of a measured period of time after said track relay becomes energized.

9. In combination, a section of railway track, a railway signal for governing traffic movements onto said section, a track circuit for said section including a track relay, a control circuit including a front contact of said track relay for controlling said signal to display a proceed indication, a directional stick relay, a pickup circuit controlled by a train for energizing said stick relay when said train enters said section while said signal is displaying a proceed indication, a stick circuit including a front contact of said stick relay for then retaining said stick relay in the energized condition, means controlled by said stick relay upon becoming energized for opening said signal control circuit, time element means controlled by said track relay and by said stick relay for opening said stick circuit upon the lapse of a measured period of time after said track relay becomes energized, a second signal for governing traffic movements in the opposite direction onto said section, and a control circuit for controlling said second signal to display a proceed indication including a contact of said time element means closed when said time element means is deenergized and also including a back contact of said stick relay.

10. In combination, a section of railway track, a railway signal for governing traffic movements onto said section, a track circuit for said section including a track relay, a control circuit including a front contact of said track relay for controlling said signal for displaying a proceed indication, time element means normally deenergized, a second contact also included in said control circuit which is normally closed but which becomes opened in response to a train entering said section while said signal is controlled to display a proceed indication, means controlled by said time element means for then retaining said second contact open while said time element means is deenergized and for again closing said second contact upon the lapse of a measured period of time after said time element means becomes energized, and means including said track relay contact for effecting energization of said time element means when said track relay contact again becomes closed while said second contact is open.

11. In combination, a section of railway track, a railway signal for governing traffic movements onto said section, a track circuit for said section including a track relay, a control circuit includ-

ing a front contact of said track relay for controlling said signal for displaying a proceed indication, a second contact also included in said control circuit which is normally closed but which becomes opened in response to a train entering said section while said signal is controlled to display a proceed indication, a time element device having a contact which is normally closed but which becomes opened after said time element device has been energized a measured period of time, means for energizing said time element device if said track relay contact becomes closed while said second contact is open, and means controlled by said time element device contact for retaining said second contact open while said time element device contact is closed and for effecting the closing of said second contact when said time element device contact becomes opened.

12. In combination, a section of railway track, a railway signal for governing traffic movements onto said section, a track circuit for said section including a track relay, a control circuit including a front contact of said track relay for controlling said signal for displaying a proceed indication, a second contact also included in said control circuit which is normally closed but which becomes opened in response to a train entering said section while said signal is controlled to display a

proceed indication, a time element device having a contact which is normally closed but which becomes opened after said time element device has been energized a measured period of time, means for energizing said time element device if said track relay contact becomes closed while said second contact is open, means controlled by said time element device contact for retaining said second contact open while said time element device contact is closed and for effecting the closing of said second contact when said time element device contact becomes opened, a second signal for governing traffic movements in the opposite direction onto said section, and a control circuit for said second signal including said time element device contact and a third contact which is controlled by the same means as said second contact and is closed when said second contact is closed.
